DESIGN FOR A SWING PLUG FOR USE WITH A BUS DUCT RUN

William H. Frank, Detroit, Mich., assignor to
Bulldog Electric Products Company, Detroit,
Mich., a corporation of West Virginia

Application February 26, 1934, Serial No. 50,877

Term of patent 7 years

To all whom it may concern:

Be it known that I, WILLIAM H. FRANK, a citizen of the United States of America, and a resident of Detroit, county of Wayne, and State of Michigan, have invented a new, original, and ornamental Design for a Swing Plug for Use with a Bus Duct Run, of which the following is a specification, reference being had to the accompanying drawing.

Fig. 1 is a perspective view of the swing plug, shown in my design.

Fig. 2 is a plan view thereof.

What I claim is:

The ornamental design for a swing plug for use with a bus duct run substantially as shown.

In testimony whereof I affix my signature.

WILLIAM H. FRANK.
